UNITED STATES PATENT OFFICE.

ARTHUR COOPER, OF MIDDLESBOROUGH, COUNTY OF YORK, ENGLAND.

METAL-WORKING PLANT.

SPECIFICATION forming part of Letters Patent No. 274,911, dated April 3, 1883.

Application filed December 13, 1882. (No model.) Patented in England September 21, 1882, No. 4,508.

To all whom it may concern:

Be it known that I, ARTHUR COOPER, a subject of the Queen of Great Britain, residing at The Laurels Linthorpe, Middlesborough, in the county of York, England, have invented certain new and useful Improvements in Metal-Working Plants, (for which I have applied for Letters Patent in England, No. 4,508, dated September 21, 1882;) and I do hereby declare that the following is a full, clear, and exact description of the invention, which will enable others skilled in the art to which it appertains to make and use the same.

This invention relates to the treatment of hot steel or iron ingots immediately after casting and before they are hammered and rolled. At present the ingots after removal from the molds are usually heated in heating-furnaces. It has, however, been proposed to allow the heat of the ingots to be equalized by placing them for some time in separate cells lined with fire-brick, into which they are dropped by a crane, and from which they are lifted for transfer to the rolls when the heat is sufficiently equalized. It has also been proposed to place the hot ingot on the ground and surround it with a casing or cover till it is ready for rolling. Furthermore, annealing-tunnels of refractory material provided with trucks and movable division-walls are old for treating scoria or other vitrified matter, and ingots have been conveyed on trucks from the casting-pit through an oven and reheating-furnace to the blooming-mill.

Now my invention is in the nature of an improved arrangement and apparatus for enabling this equalization of the heat to be effected, first, with less manipulation of the ingots; secondly, with fewer repairs to the equalizing-chamber being necessary; thirdly, by a more steady and regular distribution and accumulation of heat in the equalizing-chamber; and, fourthly, with greatly-increased facilities for working, as there is no radiation of heat from the hot uncovered ingots being moved about or standing in the works; and my invention consists in the combination and arrangement of means hereinafter specifically set forth and claimed.

In the accompanying drawings, which form part of this specification, Figure 1 represents

in side elevation an advantageous arrangement when the tunnel is made below the ground or surface-level. Fig. 2 represents a plan of same. Fig. 3 represents a sectional elevation 55 of the tunnel at the part at which the ingots are removed. Fig. 4 represents an overground tunnel for a single row of ingots. Fig. 5 represents a plan of same. Fig. 6 represents a sectional elevation of Fig. 5, and Fig. 7 represents a tunnel in which the ingots are laid upon their sides therein.

To prevent the radiation of heat, the walls and roof should be very thick. The lining is preferably of the best fire-brick. The tunnel 65 or tunnels run from the casting-pit to the immediate neighborhood of the cogging or bloom-ing mill or hammer. They may be either straight or return by a curve to the casting-pit. If a straight tunnel is used, which is 70 always preferable, particularly when the dis-tance between the casting-pit and the mill is a short one, a second or return tunnel is de-sirable; or, if a large make of ingots has to be dealt with, even three or more such tun-nels may be constructed side by side, and these may be used alternately. The tunnels have easily-removable and closely-fitting fire-brick doors or dampers, *b*, dividing them into several sections, as shown. It is preferred 75 that each section should be just large enough to take one cast. The doors or dampers may be opened either by raising them vertically, as ordinary furnace-doors, or they may be ar-ranged to move horizontally, and they may 80 be made in either one or more parts. There are several modes in which the ingots can be moved along from the casting-pit to the mill, this transference in my system being always accomplished inside the tunnel with-out exposure to the air. The method I prefer 85 is that of running the ingots through the tun-nel to the mill on very low bogies, of either wrought or cast iron, running either on rollers or on wheels on a tramway, as shown at *c*, 90 Figs. 1, 3, 4, 6, and 7, the wheels or rollers be-ing protected from the heat of the ingots and the upper part of the tunnel by the bogie-plat-forms, which are sheeted with fire-brick, and so arranged that they form a joint more or 95 less air-tight with the sides of the tunnel. For this purpose I prefer that the sides of the bo-

gie-platforms project into channels or grooves formed in the tunnel sides, (see Fig. 3,) or the bogie top and sides may be in the form of an inverted box sheeted with fire-brick on the outside, the wheels running underneath, as in Figs. 4 and 6, c. The bogies which I prefer should be of such a length that one or more will just fill a section of the tunnel between two of the fire-brick dampers, so that the platforms will form a continuous surface, protecting the carriage body and wheels from the heat, and are moved along the tunnel by a chain or rope of iron or steel and a winch, or by an endless chain, or by a hydraulic ram working direct or otherwise, or by some other suitable contrivance.

The ingots may be placed on the bogies either vertically, as in Figs. 1, 3, 4, and 6, or horizontally and lengthwise, as in Fig. 7; or they may be placed crosswise on the bogies, the tunnels in each case being built so as to give a clearance in cross-section of about three inches round the ingot. Another mode of moving the ingots along the tunnel is to push them through from the casting-pit end by means of a hydraulic ram or similar device, without the use of bogies, the motion being transmitted from one ingot to the other along the whole tunnel. It is in this case desirable to diminish the friction by laying rails along the bottom of the tunnel, the rails being nearly buried in fire-brick to prevent too great heating. They may, in addition, be made hollow and kept cool by the circulation of water, (but I do not claim this as part of my invention.) When the ingots are pushed through the tunnel from the casting-pit end, as last described, it is desirable that the tunnel should have an inclination downward from the casting-pit to the rolls of at least one in fifteen. I also find that the system of casting, which, when used in conjunction with my tunnel equalizing chambers, gives the best results, is that in which the ingots are cast on trolleys or bogies, which after removal of the mold can be run with the hot ingots directly into the hot tunnel. When the casting is conducted in longitudinal pits below the ground, the hot tunnels may be made as continuations of the pits, of which a complete arrangement is shown in Figs. 1 and 2, where E represents the converters; f, the center crane for transferring the ladle g to carriage h, from which the ingots are cast in longitudinal pits i i. After the ingot-molds j are removed by cranes k k, the damper b is raised and the bogie of hot ingots is passed direct into the hot tunnels a a, and if the tunnel consists of two sections, as shown, or more than two sections, it is immediately passed forward to that one adjacent to the cogging-rolls, and as soon as the heat in the ingots has become sufficiently equalized for rolling the closely-fitting

stoppers or covers l l are removed from the apertures which I make in the roof of that part of the tunnel, and the ingots are lifted 65 out by crane m and transferred to cogging-mill rollers n. When the tunnels are constructed above the ground, as shown in Figs. 4, 5, and 6, the ends near the cogging-mill, as well as the ends near the casting-pit, are closed 70 with easily-removable and closely-fitting doors or dampers b b. As soon as the ingots forming a cast or a part of a cast have been passed into the tunnel at the casting-shop end o, the damper or door b is closed, and when the heat 75 has become sufficiently equalized for rolling, the door b at the cogging-mill end p is raised, and the bogie or bogies of ingots are moved forward until the first ingot stands just outside the tunnel in such a position that the 80 door may be shut down on the top of the bogie between the first and second ingots, thus preserving the heat in the tunnel while the first ingot is being rolled. As soon as this is done the door is again raised, and the bogies moved 85 forward until the second ingot appears outside the tunnel, when the door is shut down between the second and third ingots while the second is being rolled. The other ingots remaining are dealt with in a similar manner. 90 The ingots can be lifted from the bogies to the rolls or hammer by an ordinary ingot-crane, as shown in Figs. 1 and 2. This arrangement of doors or dampers and mode of working the ingots from the tunnels above ground is equally 95 efficient when applied to underground tunnels; but it will be apparent that in this latter case it will be necessary to make a longitudinal pit, as a continuation of the tunnels at the cogging-mill end, of sufficient length to hold 100 the bogie or bogies after the last ingot forming the cast has passed out of the end of the tunnel.

Having thus described the nature of my invention and how the same may be practically 105 employed, what I claim, and desire to secure by Letters Patent, is—

A metal-working plant consisting of the following elements: a casting-pit, a bogie containing molds, means to strip said molds from the ingots cast therein, a tunnel of refractory material, in which the heat of said ingots is equalized, movable refractory division-walls in said tunnel, inlets to said tunnel sealed with refractory doors, the blooming train rolls 110 or hammers, and means for transferring the ingots from the tunnel to the rolls or hammers, all combined and arranged substantially as and for the purpose described.

ARTHUR COOPER.
